UNITED STATES PATENT OFFICE.

WILLIAM BUSHEY, OF VINCENNES, INDIANA.

WRENCH.

SPECIFICATION forming part of Letters Patent No. 259,363, dated June 13, 1882.

Application filed November 16, 1880. Renewed May 18, 1882. (Model.)

To all whom it may concern:

Be it known that I, WILLIAM BUSHEY, of Vincennes, Knox county, and State of Indiana, have invented certain Improvements in Combination-Wrenches, of which the following is 5 a specification.

My invention relates to the combination, arrangement, and construction of parts of an improved wrench which is especially adapted to 10 use upon nuts, bolts, and tap-heads of all kinds and classes, varying in sizes from one-fourth of an inch or less to four inches, or larger, in diameter; and it will be herein more minutely 15 and fully set forth and described with reference to the accompanying drawings, in which—

Figure 1 is a perspective view of a wrench containing my invention. Fig. 2 is a longitudinal vertical section of the same. Fig. 3 is a cross-section on the line $x-x$ of Fig. 2. 20 Fig. 4 is a perspective view, on a smaller scale, of the movable jaw A.

The movable jaw A is recessed on its under side to fit the guide-rib C. C' is a recess on under side of A to fit guide-rib C.

25 My wrench consists of three distinct parts or pieces, A, B, and D, C being the guide-rib upon which the recess C' fits. A is the upper or movable portion of said wrench, and slides backward or forward upon the guide-rib C, as the operator may have occasion to 30 use the jaws at either end of said part A. B is the main stock or handle of said wrench. C is the guide-rib upon which A moves, and is a portion of B. D is a thumb-screw which 35 binds or fastens A and B together.

By moving A on C so that the jaws b on A and i on B meet the object to be held the largest "wrench" is formed, and bodies of the largest capacity of the wrench may be grasped.

40 By reversing the movement of A, so that j' on A and j on B meet the object, the jaws j' and j form a second wrench, whose use is similar to the former one, (b on A and i on B,) except that it is to be used upon bodies of a

smaller size. By means of the thumb-screw 45 D the part A is firmly pressed down on the guide-rib C on B, the serrations k' on A and k on B meeting and entering the cavities of each other. When the thumb-screw D has been thus firmly screwed down the instrument 50 is ready for use, C fitting the recess C', and k and k' meeting and entering each other assist D in binding and holding the parts A and B together, and when either the jaws b and i or j and j' are to be used, add greater strength to 55 the wrenching power of said instrument. C and C' also facilitate the moving or adjustment of A on B. On the handle of the main stock or portion of wrench B are g, larger, and g', smaller, cavities for use upon nuts, taps, and 60 bolt-heads of smaller sizes and in more difficult position than those used upon or worked by the jaws b i and j j'. At the small or handle end of B is f, a socket-wrench, whose use is similar to g and g'. Its capacity is the minimum of the instrument, as f is the smallest 65 cavity or wrench of said instrument.

What I claim as new in my wrench, and desire to secure by Letters Patent, is—

1. In combination with the part B, having 70 jaw i, guide-rib C, and serrations k, the slotted movable part A, having jaw b, serrations k', and recess C', and the clamping-screw D, passing through the slotted part A and into the part B, substantially as and for the purpose 75 set forth.

2. In combination with the part B, having 80 guide-rib C, and jaws i and j, the slotted movable part A, having jaws b and j' and recess C', and the clamping-screw D, passing through the slotted part A and into the part B, substantially as and for the purpose set forth.

In testimony whereof I affix my signature in presence of two witnesses.

WILLIAM BUSHEY.

Witnesses:

JOHN SILENCE,
JAS. P. L. WEEEMS.
